CLAIM

The ornamental design for a combined ceiling light and vent intake for bathrooms and the like, substantially as shown and described.

DESCRIPTION

FIG. 1 is a bottom perspective view of a combined ceiling light and vent intake for bathrooms and the like showing our new design;

FIG. 2 is a bottom plan view thereof on an enlarged scale;

FIG. 3 is a side elevational view thereof on an enlarged scale;

FIG. 4 is a top plan view thereof on an enlarged scale;

FIG. 5 is a bottom perspective view of a second embodiment of our new design; and

FIG. 6 is a side elevational view of the second embodiment.
